UNITED STATES PATENT OFFICE.

ALBERT KRUMWIEDE, OF WALLINGFORD, CONNECTICUT, ASSIGNOR TO H. L. JUDD COMPANY, INC., OF WALLINGFORD, CONNECTICUT, A CORPORATION OF DELAWARE.

CURTAIN-ROD BRACKET.

Application filed September 6, 1924. Serial No. 736,217.

To all whom it may concern:

Be it known that I, ALBERT KRUMWIEDE, a citizen of the United States of America, residing at Wallingford, Connecticut, have ⁵ invented a new and useful Curtain-Rod Bracket, of which the following is a specification.

My invention relates to a curtain rod bracket.

10 It is the principal object of the invention to provide a bracket for supporting a curtain rod or the like which will be very simple and cheap to manufacture, and which will be strong and serviceable.

15 It is usual to attach some form of bracket to a wall or window casing and to support the curtain rod on such brackets. My new form of bracket is preferably formed of sheet metal, bent or formed so as to provide ²⁰ an integral structure, including a supporting base plate, to be attached to a wall or window casing, and a channel-shaped tongue extending outwardly at substantially right angles thereto to be received in the end of a ²⁵ curtain rod.

In the drawings which show, for illustrative purposes only, a preferred form of the invention—

Fig. 1 is a fragmentary view of a window ³⁰ casing showing one form of my improved bracket with a curtain rod in place;

Fig. 2 is a perspective view of the supporting bracket;

Fig. 3 is a longitudinal sectional view ³⁵ through the bracket and one end of the curtain rod in place;

Fig. 4 is a cross sectional view through the end of the curtain rod shown in Fig. 3;

Fig. 5 is a plan view of the blank out of ⁴⁰ which the bracket is formed.

In said drawings, 5 represents a window casing, wall or the like, from which a curtain rod is to be supported. The bracket, indicated generally at 6, is secured to the ⁴⁵ wall and a curtain rod 7, having a hollow end, is supported from the bracket.

The bracket is preferably formed of a blank as shown in Fig. 5 including a base plate 8 which may have holes 9—9 to receive ⁵⁰ screws or nails for holding the base plate in place on a window casing. An arm 10 is integrally formed with a base plate 8, and side arms or flanges 11—11 are formed in-

integrally with the arm 10. After the blank is cut the flanges 11—11 are bent up, preferably substantially at right angles to the arm 10, and the arm 10 is preferably bent up at substantially right angles to the base plate 8. If desired, the free longitudinal edges of the flanges 11—11 may be bent or ⁵⁵ crimped in, as indicated at 12—12, for forming rounded exposed edges. The free ends of the flanges 11—11 may be cut back at an angle, as indicated at 13, so as to form a relatively reduced end to facilitate introduction into the end of the curtain rod. ⁶⁰

When it is desired to use the bracket, the base plate 8 is secured to the wall or other supporting member with the channel-shaped tongue extending preferably at substantially ⁷⁰ right angles thereto. The hollow end of the curtain rod 7 is then forced over the tongue, and the relatively reduced end of the tongue facilitates the introduction of the tongue into the hollow curtain rod. In the form ⁷⁵ shown the free end of the curtain rod is somewhat bell shaped, and a ferrule 14 may be provided for strengthening the extreme end of the rod and giving a smooth and finished appearance thereto. ⁸⁰

It will be seen that in use the flanges 11—11 will be very slightly resilient, and when the curtain rod is slipped over the tongue the four edges of the channel will engage the inside of the rod with sufficient ⁸⁵ frictional resistance to properly support the rod. I prefer to make the channel substantially rectangular in shape, so as to give four supporting edges on the inside of the curtain rod, but it will be obvious without ⁹⁰ illustration that the channel could be otherwise formed, but in all cases there should be at least three lines of contact between the bracket and the inside of the tube. The width of the arm 10 is, as plainly appears ⁹⁵ from the drawings, much less than the diameter of the tubular rod that the bracket is designed to support hence the rod will not be distorted when applied and the bracket will be better adapted to take rods of varying ¹⁰⁰ sizes than would otherwise be the case.

The entire bracket may be stamped out of sheet metal, and is exceedingly cheap to manufacture. The construction of the bracket is such that heavy curtains or draperies may ¹⁰⁵ be supported from the curtain rod without

danger of bending the bracket, even though the same be made of relatively thin sheet metal.

While I have described the invention in some detail, I do not wish to be strictly limited to the form shown, since variations may be made within the scope of the invention as defined in the appended claims.

I claim—

- 10 1. In a curtain rod bracket, a base plate, an arm integral therewith and extending outwardly therefrom, said arm being of a width substantially less than the internal diameter of the rod to be supported thereby and a flexible side flange on said arm arranged at an angle thereto and forming with

said arm a channel, said arm and flange being arranged to engage the interior of a rod along at least three lines.

2. A curtain rod bracket comprising a 20 base plate, an integral arm extending outwardly therefrom, said arm being of substantially less width than the diameter of the rod to be supported by the bracket, two flexible flanges formed on the opposite edges 25 of said arm and extending at an angle thereto from one side thereof to form a channel between them, the edges of said arm and flanges being arranged to engage the interior of a rod on four lines.

ALBERT KRUMWIEDE.
